LOOP-TAKER FOR SEWING MACHINES

George A. Fleckenstein, Stratford, Conn., assignor to The Singer Manufacturing Company, Elizabeth, N. J., a corporation of New Jersey

Application October 21, 1933, Serial No. 694,538

12 Claims. (Cl. 112—230)

This invention relates to improvements in loop-takers for sewing machines and more particularly to the type of loop-taker having a thread-case journaled in a raceway.

5 One of the objects of his invention is to provide an improved raceway for the thread-case which will yield outwardly or in a plane at right angles to the axis of movement of the loop-taker in the event that thread or other foreign material is caught in the raceway.

10 With the above and other objects in view, as will hereinafter appear, the invention comprises the devices, combinations and arrangements of parts hereinafter set forth and illustrated in the 15 accompanying drawings of a preferred embodiment of the invention, from which the several features of the invention and the advantages attained thereby will be readily understood by those skilled in the art.

20 In the drawing:

Figure 1 is a top plan view of my improved loop-taker.

25 Figure 2 is a side elevation partly in section, the section being taken substantially along the line 2—2 of Figure 1.

Figure 3 and 4 are side elevations, and Figure 5 is a disassembled perspective view of the component parts of the loop-seizing member.

30 In the embodiment of this invention selected for illustration, 1 is the well-known vertical-axis loop-taker driving shaft which has fixed to its upper end the usual cup-shaped loop-taker body 2 which is formed with a gap 2' and a flange 3 having one of its ends terminating in a loop-seizing beak 4 and its other end terminating in a vertical wall 5. The loop-taker body 2 is provided with a bearing seat 6 for the bearing rib 7 of the usual thread-case 8 having a finger 9 engaging the usual rotation restraining bar 10.

35 Fixed to the loop-taker body 2 by the pivot-pin 11 is an arcuate member 12 having a depending stud 13 which is adapted to enter the peripheral opening 13' formed in the hook-body 2. The arcuate member 12 and flange 3 together form a continuous circular flange on the hook-body, the member 12 being, in effect, a section of the flange. A flat spring 14, forming a needle-guard, has one of its ends fixed to the loop-taker body 2 by means of the screws 15 and bridges the gap 2' of the hook-body adjacent the loop-seizing beak. The free end of the needle-guard 14 extends over the stud 13 and is held against sidewise movement by the ribs 16 formed on the loop-taker body 2. A cover-ring formed in two sections 18 and 18' 40 prevents vertical movement of the thread-case

8 in the loop-taker body. The section 18 is fixed to the flange 3 by means of the screws 19 and extends over the vertical wall 5 of the flange 3 thus serving to hold one end of the arcuate member against the loop-taker body. The other section 18' is fixed to the arcuate member 12 by means of the screws 20.

5 It will be evident to those skilled in the art that the free end of the arcuate member 12 is yieldingly urged towards the loop-taker body by 10 means of the flat spring or resilient needle-guard 14 and that this member 12 will yield outwardly in the event that thread or other foreign material is caught between the bearing rib 7 of the thread-case and the wall of the arcuate member 15 12. It will also be evident that thread caught between the flange 3 on the hook-body and the bearing rib 7 of the thread-case will shift the thread-case laterally or in a plane at right angles to the axis of rotation of the hook, the yielding 20 arcuate member 12 permitting the shifting movement of the thread-case.

Having thus set forth the nature of the invention, what I claim herein is:

1. A loop-taker for sewing machines including a circular member provided with a flange a portion of which is radially yieldable, and a spring secured to the outer periphery of said member for yieldingly holding the radially yieldable portion of said flange in its normal position.

2. A loop-taker for sewing machines including a circular member provided with a flange formed in two sections, one of said sections being fixed to said member and the other section having one of its ends pivoted to said member and its other end urged inwardly by a flat spring fixed to the outer periphery of said member.

3. A loop-taker for sewing machines including a circular loop-seizing element formed with a flange having one end terminating in a loop-seizing beak and its other end terminating in an upstanding wall, an arcuate member having one of its ends pivoted to said element adjacent the upstanding wall and spring means fixed to the outer periphery of said element for constantly urging the free end of said arcuate member against said element.

4. A loop-taker for sewing machines comprising a loop-seizing member movable about an axis, and provided with a flange having a plurality of sections forming a raceway, one of said sections being fixed to said member and the other of said sections being secured to said member for movement in a plane at right angles to the axis of movement of said member, spring means fixed

- to the outer periphery of said member for yieldingly holding said last mentioned section in its normal position, and a thread-case having a bearing rib journaled in said raceway.
5. A circular moving hook for sewing machines formed with a loop-seizing beak and a circular raceway having a gap therein adjacent the point of said beak, a thread-case having a bearing rib journaled in said raceway, the raceway forming portion of the hook including a movable section pivotally connected to the hook-body and a flat spring bridging the gap in the raceway for yieldingly holding said radially movable section in its normal position.
10. A circular moving hook for sewing machines comprising a cup-shaped hook-body formed with a bearing seat, and an upstanding annular wall, a portion of the wall being yieldable in a plane at right angles to the axis of movement of said hook, a thread-case having an annular bearing rib supported by said seat, and a cover-ring for maintaining said bearing rib on said seat and within the area defined by said upstanding wall.
15. A circular moving hook for sewing machines formed with a loop-seizing beak and a circular raceway having a gap therein adjacent the point of said beak, a thread-case having a bearing rib journaled in said raceway, the raceway forming portion of the hook including a movable section pivotally connected to the hook-body and a resilient needle-guard bridging the gap in the raceway for yieldingly holding said radially movable section in its normal position.
20. A loop-taker for sewing machines including an annular member formed with a flange having one end terminating in a loop-seizing beak and formed with a raceway, an arcuate element having one of its ends pivoted to said member for movement in a plane at right angles to the axis of rotation of said loop-taker, a stud carried by said element and a flat spring having one end fixed to said annular member and its other end overlying the stud for resiliently holding said arcuate element in its normal position.
25. A circular moving loop-taker for sewing machines including an annular member provided with a flange formed in two sections, each section forming a portion of a raceway, at least one of said sections having one of its ends pivotally secured to said member and its other end yieldingly held in engagement with said member by means of a resilient needle-guard.
30. A circular moving hook for sewing machines having a loop-seizing beak and a circular raceway formed with a gap therein adjacent the point of the beak, a thread-case having a bearing rib journaled in said raceway, the raceway forming portion of the hook including an arcuate member pivotally connected to the hook-body, a stud carried by said arcuate member, and a flat spring carried by the hook-body and engaging said stud.
35. A circular moving hook for sewing machines comprising a hook-body formed with a bearing seat and a flange having one end terminating in a loop-seizing beak, an arcuate member having one end pivoted to said hook, a stud carried by the free end of said arcuate member, a spring fixed to said hook-body and engaging said stud to maintain said arcuate member in its normal position, a thread-case having an annular bearing rib supported by said bearing seat, and a cover-ring for confining said bearing rib in said hook-body.
40. A circular moving hook for sewing machines comprising a hook-body formed with a bearing seat and a flange having one end terminating in a loop-seizing beak, an arcuate member having one end pivoted to said hook-body, a stud carried by the free end of said arcuate member, a spring having one end fixed to said hook-body and its free end engaging said stud to maintain said arcuate member in its normal position, and elements carried by said hook-body for holding the free end of said spring against movement in a direction parallel to the axis of movement of said hook.

GEORGE A. FLECKENSTEIN.
